CLAIM

The ornamental design for a foot plate for drum pedal, as shown and described.

DESCRIPTION

FIG. 1 is a perspective view of a foot plate for drum pedal showing my new design;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof; and,

FIG. 8 is a perspective view thereof showing the design as used.

The broken lines represent the portions of the foot plate for drum pedal that form no part of the claimed design. Non-oblique line shading is meant to show contour and not surface ornamentation.
